UNITED STATES PATENT OFFICE

133,355

DESIGN FOR A SEAT SPRING UNIT

Everett S. Tallmadge, Granville, Wis., assignor
to Flexsteel Spring Corporation, Minneapolis,
Minn., a corporation of Minnesota

Application April 13, 1942, Serial No. 106,563

Term of patent 14 years

To all whom it may concern:

Be it known that I, Everett S. Tallmadge, a citizen of the United States of America, residing at Granville, in the county of Milwaukee and State of Wisconsin, have invented a new, original, and ornamental Design for a Seat Spring Unit, of which the following is a specification, reference being had therein to the accompanying drawing, forming a part thereof, wherein:

Figure 1 is a perspective view of a seat spring unit, showing my new design;

Figure 2 is a side elevational view; and

Figure 3 is an end elevational view thereof.

I claim:

The ornamental design for a seat spring unit, substantially as shown.

EVERETT S. TALLMADGE.
